LAWN MOWER HANDLE

Norman W. Schultz, Torrance, Calif., assignor to Lawncraft Co., Inc., Torrance, Calif.

Application September 9, 1957, Serial No. 47,648

Term of patent 14 years

(Cl. D40—1)

The broken line portions of the drawing are depicted for illustrative purposes only.

I claim:

The ornamental design for a lawn mower handle, substantially as shown and described.
